UNITED STATES PATENT OFFICE.

WILLIAM JACKSON BURNETT, OF THOMASVILLE, GEORGIA.

PLOW.

Application filed May 24, 1922. Serial No. 563,325.

To all whom it may concern:

Be it known that I, WILLIAM J. BURNETT, a citizen of the United States, residing at Thomasville, in the county of Thomas and State of Georgia, have invented a new and useful Plow; of which the following is a specification:

This invention relates to plows and is designed more particularly as an improvement upon the structure disclosed in my copending application.

One of the objects of the invention is to provide means whereby wings or sweeps can be adjustably connected to the lower end of the stock or standard of the plow, there being a runner likewise connected to said portion of the standard and capable of angular adjustment with or independently of the wings.

Another object is to so locate the sweeps or wings that they will be positioned close to and can act in conjunction with the point of the plow.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred forms of the invention have been shown.

In said drawings—

Figure 1 is a side elevation of a plow having the present improvements combined therewith.

Figure 2 is a vertical longitudinal section.

Figure 3 is a section on line 3—3, Figure 2, the plow point and the handles being removed.

Figure 4 is a plan view of the runner, the lower portion of the standard being shown in section.

Figure 5 is a side elevation of a portion of the standard and showing a modified form of runner.

Figure 6 is a section on line 6—6, Figure 5.

Referring to the figures by characters of reference 1 designates a portion of a plow beam having a downturned standard por-

tion on opposite faces of which are arranged parallel extension strips 3 which extend downwardly beyond the lower end of the portion 2 of the beam. Mounted on the outer side faces of these strips are plates 4 and the two plates as well as the strips 3 are fastened to the standard portion 2 by means of transverse bolts 5 extending through them. Handles 6 are pivotally connected to the plates 4 by a transverse bolt 7 and brace strips 8 connect these handles 6 to a sleeve 9 slidable on the beam 1 and adapted to be fastened in any desired position by a set screw 10.

The lower portions of the strips 3 are cut away along their rear edges as shown at 11 and extending through the lower ends of these strips are pivot bolts 12 and 13. Arcuate slots 14 are formed in the strips and are concentric with the bolt 13.

Extending between the strips 3 and pivotally mounted on the bolt 12 is a tongue 15 extending from the forward end of a runner 16, this tongue being preferably formed of a separate piece of metal secured to the runner by means of rivets 17 as shown in Figure 4 although it is to be understood that if desired the tongue and runner can be made in one piece. Ears 18 extend from the rear portion of the runner and pivotally mounted between them is one end of a rod 19. This rod is slidable within a sleeve 20 having an ear 21 pivotally fastened between the plates 4 by a bolt 22. A set screw 23 is carried by the sleeve 20 and engages rod 19 to hold it against longitudinal movement. If desired the rod can be screw threaded as shown for engagement by the set screw 23, thus to further insure the proper holding of the rod when engaged by the set screw.

The pivot bolt 13 extends through ears 24 extending upwardly from the front portions of wings or scrapers 25 and are obliquely disposed relative thereto. These ears are also engaged by a clamping bolt 26 extending through the slots 14. By loosening bolt 26 the wings or scrapers 25 can be adjusted angularly and by tightening the bolt the parts will be held securely in the positions to which they have been adjusted.

It will be noted that the plow point 27 is secured to the strips 3 by the usual heel bolt 28 but by mounting the wings or scrapers 25 as described they can extend close to and

back of the point and will cooperate therewith to produce the desired action on the loosened soil.

Instead of having a tongue 15 extending between the strips 3, the runner 29 can have a forked front end 30 straddling the strips 3, this forked end being formed with a segmental contour as shown in Figure 5 and being held to the strips 3 by a pivot bolt 31. Arcuate slots 32 are formed in the segmental portions of the runner, the inner faces of these segmental portions being countersunk along the slots as shown at 33 to receive the heads 34 of clamping bolts 35. Said bolts extend through the ears 36 of the wings or scrapers 37 and which ears are mounted on the pivot bolt 31. Thus by loosening the bolts 35 the wings or scrapers can be adjusted angularly about bolt 31 after which they can be secured by tightening the bolts 35 as well as bolt 31. In this modified structure both the wings and the runner are mounted on the same pivot bolt but these parts can be adjusted angularly relative to each other and to the strips 3, as will be obvious.

Importance is attached to the particular construction of each of the wings or scrapers 25. Each of these devices has an ear 30 standing at an angle thereto and obliquely disposed with reference to the longitudinal axis of the blade so that when the device is applied to a standard it is held at the proper angle for cultivating. The scrapers or wings can be of any length desired and the ears thereon are so shaped that they can be applied readily to a standard 3 or to a runner 29. These scrapers can be used either singly or in pairs. Furthermore a long scraper can be used on one side and a short

scraper can be used at the other side of the plow. This is particularly advantageous where a farmer desires to use a short scraper close to the corn or cotton and a long scraper for the purpose of cleaning the space between the rows. Thus it is not necessary to make two trips along a row to cultivate the plants and to clean the space between the rows. 45

What is claimed is:—

1. In a plow the combination with a standard and parallel extension strips secured thereto, of a runner pivotally connected to said strips, wings or scrapers pivotally connected to the strips, and clamping means for holding said wings or scrapers against angular adjustment, there being arcuate slots for the reception of the clamping means concentric with the point of connection between the wings and the strips. 50

2. In a plow the combination with a standard, extension strips thereon and a point secured to the strips, of an angularly adjustable runner pivotally connected to the strips close to and back of the point, a wing or scraper mounted for angular adjustment relative to said strips about an axis located back of and close to the point and extending through the lower portions of the strips, and means for holding said wing or scraper in any position to which it may be adjusted. 55

In testimony that I claim the foregoing as my own, I have hereto affixed my signature in the presence of two witnesses.

WILLIAM JACKSON BURNETT.
